LIGHTER CONSTRUCTION FOR GAS RANGES

William H. Guenther and Henry C. Maul, Detroit,
Mich., assignors to Detroit-Michigan Stove
Company, Detroit, Mich., a corporation of
Michigan

Application August 6, 1934, Serial No. 738,752

5 Claims. (Cl. 158—115)

This invention relates generally to lighter constructions for gas ranges and refers more particularly to flash lighter constructions for the gas burners of stoves and ranges.

Heretofore in an endeavor to insure proper relation of the lighter to the burners the lighter tubes have been combined or formed integral with enameled burner trays, and the combined trays and lighters have been received within the burner compartments of the ranges between the pans at the bottom of said compartments and the grates at the top thereof. However, in use such combinations are impractical, primarily because the trays become too hot for the enamel thereon and cause it to crack and chip off. Moreover, the constructions have been such that the burners themselves become hotter than usual due to the chimney effect for air produced by the burner tray and lighter combinations about the burners, and such conditions result in objectionable popping noises when the supply of gas to the ignited burners is cut off.

Therefore, it is an object of the present invention to provide a lighter construction that is not only separate from and free of the burner tray, but is constructed and arranged in such a way relative to the burners and trays that the latter may retain their enamel finish, and the objectionable popping noises referred to will be substantially dispensed with.

Another object of the invention is to provide a lighter construction which enables the burner tray to be readily removed for cleaning or other purposes and affords the proper access to the burners to permit them to be cleaned, repaired or replaced as desired.

Another object is to provide a lighter construction which preferably includes a number of auxiliary burners which are constructed and arranged in such a way that they may be alternatively used as simmering burners and as lighters for the main burners.

Another object is to provide a lighter construction wherein the auxiliary burners are adapted to cooperate with the main burners to provide heat for cooking purposes.

Another object is to provide a lighter construction that is combined with the burner compartment bottom or pan which is rigid with the framework of the range so that the lighter will always be in proper position.

Another object is to provide a lighter construction wherein the pan just mentioned not only carries the lighter parts, but also serves

as a support for the main burners and removable burner tray.

Other objects, advantages and novel details of construction of this invention will be made more apparent as this description proceeds, especially when considered in connection with the accompanying drawings, wherein:

Figure 1 is a fragmentary perspective view of a gas range having a lighter construction embodying our invention;

Figure 2 is a sectional view taken substantially on the line 2—2 of Figure 1;

Figure 3 is a sectional view taken substantially on the line 3—3 of Figure 1;

Figure 4 is a bottom plan view of the burner compartment and associated lighter structure;

Figure 5 is a sectional view taken substantially on the line 5—5 of Figure 4;

Figure 6 is a cross sectional view taken on the line 6—6 of Figure 5;

Figure 7 is a cross sectional view taken on the line 7—7 of Figure 5;

Figure 8 is a sectional view taken substantially on the line 8—8 of Figure 4;

Figure 9 is a perspective view of the plug 69;

Figure 10 is a cross sectional view taken on the line 10—10 of Figure 2;

Figure 11 is a cross sectional view taken on the line 11—11 of Figure 2.

Referring now to the drawings, A is a gas range having a cooking top frame B, and a burner supporting pan C within and supported from said frame. Preferably the bottom 1 and sides 2 of this pan C are formed from a single sheet of metal and are located a predetermined distance below the top of the frame B. The pan C is preferably provided with an upstanding marginal flange 3 that is rigid with the frame B. The bottom 1 of the pan C is provided at the center thereof with an opening 4 and is provided adjacent its four corners with suitable openings 5 for the reception of main burners D, while the sides 2 of the compartment have stepped ledges or shoulders 6 and 7 respectively upon which a suitable grate E and an enameled burner tray F are removably supported.

H is a pilot burner housing suspended from the bottom 1 of the pan C about the central opening 4, and I are tubes extending radially from said housing H to points beneath the burners D. Preferably these tubes I are formed by providing the bottom 1 of the pan with inverted channel-shape portion 10 and by securing to the underside of said bottom a sheet metal spider or plate J having cooperating channel-shape por-

tions 11. 12 is an inverted cup-shape cap for the housing H and is preferably sleeved upon an upstanding flange 13 at the edges of the opening 4. Preferably said cap 12 has a plurality of 5 vents 14 therein. 15 is a substantially frusto-conical flange extending upwardly from the edges of an opening 16 in the spider J.

K is a pilot burner within the housing H supported upon and adapted to receive gas from 10 the stem 20 of an inverted T-shape fitting L. As shown, the burner K is within and terminates just below the upper edges of a frusto-conical 15 shield 21 within the housing H, and openings 22 for air are provided in the sides of the housing below the upper edges of the shield 21 whereby the pilot burner K will make a Bunsen flame which will extend upwardly through the opening 16 to a point slightly above the upper edges 20 of the frusto-conical flange 15. The stem 20 of the fitting L extends downwardly through a plate 23 fastened to the bottom 24 of the housing H and is fastened to said plate by a suitable nut 25. The base 26 of the fitting is substantially parallel to the plate 23 and is provided with 25 an inlet 27 for gas and a manually operable needle valve 28 for regulating the passage of gas through said inlet.

M are auxiliary burners fastened by nuts 30 to arms 31 of the spider beneath and in vertical 30 alignment with central openings 32 in the main burners. As shown, these auxiliary burners M are provided at their upper ends with vertical jets 33 from which flames may extend upwardly and into the openings 32 in the main burners, 35 and are provided at one side with horizontal jets 34 that are in alignment with and open into the outer ends of the tubes I. Preferably each auxiliary burner M has a depending mixing chamber 35 provided in one side with an inlet 36 for air 40 and provided in its lower end with an interiorly threaded portion 37 receiving the exteriorly threaded portion 38 of a gas jet 39. A rotatable spring steel sleeve 40 having an opening 41 registrable with the air inlet 36 and having an operating tab 42 is preferably employed for controlling the air inlet 36, while a needle valve 44 having a stem 45 threadedly engaging the lower portion 46 of the gas jet 39 is preferably used to control the flow of gas from the inlet 47 in one side 50 thereof to the mixing chamber 35. As shown, the lower end of the stem 45 extends below the lower portion 46 of the jet so that it may be readily operated and is normally concealed by a suitable cup-shape cap or cover 48.

55 The main burners D correspond to those set forth in our application filed August 6, 1934, bearing Serial No. 738,753. Preferably each burner has a sheet metal shell 50 containing a suitable diaphragm 51 and having a plurality of 60 jets 52 in the top 53 thereof. The shells 50 are supported by flanges 54 which rest upon the bases 55 of L-shape tongues 56 depending from the bottom I of the burner compartment, and by posts 58 which extend downwardly from the shells and 65 engage suitable holes 59 in the spider arms 31.

In the present instance gas is supplied to the burners K, M and D, respectively, from a suitable manifold N in front of the burner compartment C. As shown, a pipe 60 extends from the manifold N to the base 26 of the T-fitting L. No valve 70 is provided between the manifold N and fitting L for regulating the flow of gas. Hence, the supply of gas to the burner K is under the control of the valve 28 in the fitting L. However, the supply

of gas to the burners M and D is preferably under the control of valves O mounted on the manifold N. As shown, each valve O has a casing 65 provided with an inlet 66 and two outlets 67 and 68, respectively. A rotary plug 69 within the casing 65 has an inverted L-shape passage 70 for establishing communication between the inlet 66 and outlet 67; and has a transversely extending narrow slot 71 therein for establishing communication between an inlet by-pass 72 and the outlet 68. Normally the plug 69 cuts off the supply of gas from the inlet 66 to the outlets 67 and 68. Upon being turned from closed position, the slot 71 in the plug will first open communication between the inlet by-pass 72 and the outlet 68. Subsequently while communication is still open between the inlet 66 and the outlet 68, the passage 70 and the plug will establish communication with the outlet 67. Thus, gas may be cut off from both outlets 67 and 68; may be supplied to the outlet 68 alone; 20 and finally may be supplied to both outlets 67 and 68.

80 are tubes leading from the outlets 67 of the valves to the mixing tubes 81 of the main burners, while 82 are tubes leading from the outlets 68 of the valves to the inlets 47 of the gas jets 39. Preferably the tubes 80 are supported by hangers 83 depending from the bottom I of the pan and are provided within the mixing tubes 81 with conical ends 84 and gas apertures 85. Nipples 86 of conventional configuration are adjustably mounted on the conical ends 84 of said tubes for regulating the flow of gas from the tubes to the mixing tubes 81 of the burners.

In use, the flow of gas from the manifold N to the pilot burner K is regulated by the valve 28. Normally the valves O are closed. However, upon opening said valves O, gas will initially flow to the auxiliary burners M where it will flow through both jets 33 and 34. Owing to the pressure of the mixed air and gas in the mixing chambers 35, the mixture discharged from the jets 34 will flow through the tube I to the Bunsen flame of the pilot burner K where it will be ignited. The resulting flames will flash back 45 through the tubes I to the auxiliary burners M and will ignite the mixture discharged from the jets 33. If the valves O are left in the initial open position with only the slots 71 connecting the inlet 66 and outlet 68, the auxiliary burners M 50 will be used as simmering burners as the flames therefrom will extend upwardly through the central openings 32 in the main burners to function in such manner. However, if the valves O are opened further so that the passages 70 establish 55 communication between the inlets 66 and outlets 67, then gas will flow to the main burners D and upon flowing through the jets 53 will be ignited by the flame from the auxiliary burners M. If the valves O are left in fully open position, gas will flow to the auxiliary and main burners M and D, respectively, for cooking purposes.

Actually the flames from the auxiliary burners M are substantially shielded by the main 65 burners D and associated lighter parts. However, if the flames from the auxiliary burners M are extinguished accidentally while functioning for simmering purposes, for instance by being blown out, the mixture from the jets 33 will again 70 be ignited by the ignited mixture from the jets 34. Likewise, if the main burners D should be extinguished accidentally, the mixture from the jets 53 would be ignited by the flames from the auxiliary burners M. Thus, either or both burn- 75

ers M and D will be lighted automatically when a supply of gas thereto is open and the pilot burner K is lighted.

What we claim as our invention is:

- 5 1. In a gas range, a cooking top frame, a burner pan within said frame, a removable burner tray within said pan in spaced relation to the bottom thereof and having a burner opening, a main burner carried by the bottom of said pan within the opening in said tray, a pilot burner carried by the bottom of said pan beneath said tray, an auxiliary burner carried by the bottom of said pan beneath said tray for igniting said main burner, and means forming with the bottom of said pan beneath the tray a flash tube for conducting flame from the pilot burner to said auxiliary burner.
- 10 2. In a gas range, a cooking top frame, a burner pan within and rigid with said frame, a main burner carried by said pan, a pilot burner suspended from the bottom of said pan out of igniting relation to said main burner, an auxiliary burner carried by the bottom of said pan in lighting proximity to the main burner, and means rigid and forming with the bottom of said pan a flash light tube between the pilot burner and auxiliary burner.
- 15 3. In a gas range, a cooking top frame, a burner pan within said frame, a removable burner tray within said pan in spaced relation to the bottom thereof and having a burner opening, a main burner carried by the bottom of said pan within the opening in said tray, a pilot burner carried by the bottom of said pan beneath said

tray, a member forming with the bottom of said pan beneath said tray a flash tube for conducting flame from the pilot burner toward the main burner, and an auxiliary burner carried by an extension of said member at the discharge end 5 of said flash tube in lighting proximity to the main burner.

4. In a gas range, a cooking top frame, a burner support within and carried by said frame, a removable burner tray carried by said frame 10 above said burner support and having a burner opening, a main burner carried by said burner support within the opening in said tray, a pilot burner carried by said burner support beneath said tray, means carried by the burner support 15 for conducting flame from the pilot burner toward the main burner, and an auxiliary burner carried by an extension of said conducting means at the discharge end thereof in lighting proximity to the main burner. 20

5. In a gas range, a cooking top frame, a burner pan within and rigid with said frame, a plurality of main burners carried by said pan at spaced points thereof, a pilot burner suspended from said pan out of igniting relation to said 25 main burners, a spider fastened to the underside of said pan, and auxiliary burners carried by said spider in lighting proximity to the main burners; portions of said spider forming with the underside of said pan flash tubes between the 30 pilot burner and auxiliary burners.
